UNITED STATES PATENT OFFICE.

HENRY J. GRAF, OF EAST ST. LOUIS, ILLINOIS.

FLASK.

SPECIFICATION forming part of Letters Patent No. 510,172, dated December 5, 1893.

Application filed June 12, 1893. Serial No. 477,278. (No model.)

To all whom it may concern:

Be it known that I, HENRY J. GRAF, of East St. Louis, St. Clair county, State of Illinois, have invented certain new and useful Improvements in Flasks, of which the following is a full, clear, and exact description, reference being had to the accompanying drawings, forming a part hereof.

My invention relates to improvements in "flasks" or more specifically "flask clamps" and consists in the novel arrangement and combination of parts as will be more fully hereinafter described and designated in the claims.

The object of my invention is to provide certain improvements so as to enable flasks such as are commonly used in foundries to become interchangeable and also to provide a flask clamp that is adjustable, detachable and portable, thus obviating breakage and repairage.

I will give a further description of the object of my invention in connection with a mechanical description thereof.

In the drawings: Figure 1 is a longitudinal vertical mid-section taken through the parts of the flask, that is the upper part or the cope and the lower part or the drag and also through the clamps which are secured to the ends of said parts. Fig. 2 is a detail perspective view of the detachable ear which is secured to the cope. Fig. 3 is a detail perspective view of the detachable ear which is secured to the drag. Fig. 4 is a detail perspective view of a detachable clamp which is normally mounted on the ear as illustrated in Fig. 3.

Referring to the drawings: 1 indicates the upper part or cope of the flask, and 2 indicates the lower part or drag of the flask, it being noted in this connection that the description herein relates to what is commonly known as a two-part flask.

As the clamping mechanism, or more specifically the ears which are secured to the ends of the cope are the same I will only give a description of one, and furthermore as the ears which are secured to the ends of the lower part or drag of the flask are the same, I will only give a description of one.

3 indicates the ends of the cope and secured to the lower external portion of said ends are detachable ears 4. Said ears are provided

with perforations or apertures 5, through which screws or bolts 6 may be inserted for the purpose of securing said ears to the ends 55 3. Said ears 4 are provided with an approximately U-shaped depression 7 for the purpose more fully hereinafter described, and also with strengthening ribs or webs 8 so as to increase the strength and stability of said 60 ears in a manner apparent.

9 indicates detachable ears which are detachably secured to the upper external surface of the drag 2. Said detachable ears 9 are provided with perforations or apertures 65 10 through which bolts or screws or rivets may be inserted for securing said ears to the ends 11 of the drag 2. The ears 9 are provided with a rectangular depression 12 for the purpose more fully hereinafter described. 70

In Fig. 4 I have shown a detachable clamping mechanism which is mounted on the ears 9. Said clamping device consists of a plate 13, the same being mounted on a tapering stud 14, the said tapering stud provided at 75 its opposite end with a screw threaded portion 15, the same adapted to receive a nut 16. Mounted on said screw threaded portion 15 is a detachable plate 17.

When the clamping device is in use the 80 horizontal portion 18 of the ears 9 is located between these two plates and may be clamped therein by the agency of the nut mounted on the screw threaded portion 15. When the said clamping device is in use the screw 85 threaded portion 15 is located in a rectangular depression 12, and as said rectangular depression 12 is considerably larger in dimensions than the said screw threaded portion it can be readily perceived that the said screw 90 threaded portion may be adjusted within said rectangular depression. In other words the clamping device as illustrated in Fig. 4 is detachable from and also adjustable on the ears 9. 95

When the clamping device is in use the tapering portion of the stud 14 is located in the U-shaped depression 7 of the ears 4, and when so located the cope 1 may be readily applied or placed upon and removed from the 100 drag 2 without in any manner affecting the clamping device.

It can be readily seen from the above description, that by the employment of my con-

struction of flask-clamp the unequal construction of the cope and drag will not interfere in any manner with the operativeness and the adjustment of the flask clamp.

5 Having fully described my invention, what I claim is—

1. The improved flask-clamp, comprising a stud tapered at one end and screw-threaded at its opposite end, a nut mounted upon said 10 screw-threaded end, two clamping-plates mounted upon said stud, one adjacent said nut, and means for limiting the movement of said plates toward said tapering end, substantially as herein specified.

2. A flask clamp consisting of a detachable 15 ear provided with a U-shaped depression and strengthening ribs, a detachable ear provided with a rectangular depression, a plate carrying a tapering stud provided with a screw threaded portion, a detachable plate and a 20 nut, substantially as set forth.

In testimony whereof I affix my signature in presence of two witnesses.

HENRY J. GRAF.
